[57] **CLAIM**

The ornamental design for an extension cord reel, as shown and described.

DESCRIPTION

FIG. 1 is a perspective view of an extension cord reel, in carrying condition, showing my new design;

FIG. 2 is a top plan view of my invention, in horizontal operative condition;

FIG. 3 is a bottom plan view of FIG. 2;

FIG. 4 is a right side elevational view of FIG. 2;

FIG. 5 is a left side elevational view of FIG. 2;

FIG. 6 is a front side elevational view of FIG. 2; and,

FIG. 7 is a rear side elevational view showing the side opposite to the view of FIG. 6.

The electric cord is shown broken away in FIGS. 1-3 and 6-7 to indicate indeterminate length.
